(57) **CLAIM**

The ornamental design for an exercise climbing machine, as shown and described.

DESCRIPTION

FIG. 1 is a front perspective view of an exercise climbing machine showing my new design in a folded configuration; FIG. 2 is a front elevation view thereof in a folded configuration;

FIG. 3 is a rear elevation view thereof in a folded configuration;

FIG. 4 is a right side elevation view thereof in a folded configuration;

FIG. 5 is a left side elevation view thereof in a folded configuration;

FIG. 6 is a top view thereof in a folded configuration;

FIG. 7 is a bottom view thereof in a folded configuration;

FIG. 8 is a rear perspective view thereof in a folded configuration;

FIG. 9 is a front perspective view thereof in an unfolded configuration;

FIG. 10 is a front elevation view thereof in an unfolded configuration;

FIG. 11 is a rear elevation view thereof in an unfolded configuration;

FIG. 12 is a right side elevation view thereof in an unfolded configuration;

FIG. 13 is a left side elevation view thereof in an unfolded configuration;

FIG. 14 is a top view thereof in an unfolded configuration;

FIG. 15 is a bottom view thereof in an unfolded configuration; and,

FIG. 16 is a rear perspective view thereof in an unfolded configuration.
